UNITED STATES PATENT OFFICE.

WILFRED O. CHASE, OF REDFORD, MICHIGAN, ASSIGNOR TO STEWART-WARNER SPEEDOMETER CORPORATION, OF CHICAGO, ILLINOIS, A CORPORATION OF VIRGINIA.

VACUUM TANK.

Application filed October 2, 1922. Serial No. 591,920.

To all whom it may concern:

Be it known that I, WILFRED O. CHASE, a citizen of the United States of America, residing at Redford, in the county of Wayne, 5 and State of Michigan, have invented certain new and useful Improvements in Vacuum Tanks, of which the following is a specification, reference being had therein to the accompanying drawings.

- 10 The invention relates to vacuum tanks more particularly designed for the supply of liquid fuel to internal combustion engines, and of that type in which the actuation and control of the movable parts is 15 pneumatic. It is the object of the invention to obtain a construction which is more positive in its operation than constructions heretofore used and which is also free from certain defects of such prior constructions. 20 To this end the invention consists in various features as hereinafter set forth.

In the drawings:

Figure 1 is a vertical central section through a vacuum tank of my improved construction;

Figure 2 is a similar view showing the parts in different positions of adjustment;

Figure 3 is a perspective view of the shield for the float detached;

30 Figure 4 is a section through the fuel inlet screen.

In general construction my improved tank comprises the casing A which is divided by a partition B into upper and lower compartments C and D. The upper compartment is closed by a head E, which has preferably formed therein the various ports, chambers and passages for the pneumatic control mechanism and the fluid supply.

40 In detail, the head E is provided with the vacuum connection F communicating with a laterally extending passage G with upwardly and downwardly extending aligned ports G' and G². H and H' are 45 valves for respectively closing said ports, the former being arranged to seat by gravity and the latter being mounted on the stem I of the float J located in the upper chamber C. The stem I loosely fits a guide bearing 50 I' at its upper end and at its lower end beneath the float is preferably provided with a guide spider I² engaging a tubular fitting K forming the outlet from the upper to the lower chamber. This outlet is nor-

mally opened, but is provided with the upwardly seating gravity released valve L, 55 this being preferably of inverted cup-shape so as to be actuated in seating by an upward current of either air or liquid. Below the valve L is a contracted neck or 60 nozzle L' for discharging the liquid stream in unbroken column.

The valve H' has extending above the portion which engages the valve seat a 65 tapering portion H² which variably restricts the area of the port forming a metering device. H³ is a lateral port extending through the guide bearing I', which is so arranged as to be closed or greatly restricted when the valve is adjacent to its seat, but fully 70 opened in the lowered position of said valve and float K. The valve H is mechanically unseated upon the seating of the valve H' by the upward extension H² and, on the other hand, the valve H' is held from seating by the valve H when the latter is seated. Thus to shift or reverse the valves H and H', each must overcome the resistance of the other as will be hereinafter set forth.

The port G', when opened by the unseating of the valve H, communicates with a 80 passage M connecting with a vertically arranged cylindrical passage N containing a gravity seating valve O for controlling a port O' communicating with the upper chamber 85 C. Extending laterally from this chamber N is an atmospheric connecting passage P, the arrangement being such that the lifting of the valve O by suction when the valve H is unseated will open the port O' and 90 vent the upper chamber C to atmosphere.

With the construction as thus far described, in the initial position of parts the valve L is unseated, leaving an open passage between the upper and lower compartments C and D. The float J is in its lower position, which unseats the valve H' and opens the port H³, establishing communication between the same and the port G². The latter, in the unseated position of the valve H', is in free communication between the 100 vacuum connection F, so that whenever suction occurs, it is communicated through said ports to the chamber C, causing an upward current (first of air) through the fitting K 105 impinging on the inverted cup-shaped valve L. This will lift said valve to its seat, thereby stopping further upward flow and

creating a vacuum in the upper chamber. This chamber is connected with a supply tank through a conduit Q and therefore the liquid fuel will be drawn into said chamber and will exert an upward pressure upon the float J, causing it to rise until the tapering portion H² of the stem comes in contact with the valve H. This will restrict the vacuum connection between the conduit F and the chamber C, both by reason of the restriction in the area of the port G² and the obstruction of the port H³. Further rise of the float is temporarily resisted by the valve H, which is held to its seat by atmospheric pressure as opposed to the vacuum on its lower side. Consequently, the parts remain stationary until the hydrostatic pressure on the float is sufficient to overcome this resistance, whereupon the valve H is unseated and the valve H' engages its seat. The unseating of the valve H communicates the vacuum to the cylindrical chamber N, lifting the valve O and opening the port O', which admits atmospheric pressure to the chamber C. This permits the valve L to drop by gravity and the liquid in the upper chamber to discharge through the open fitting K and nozzle L'. From the lower chamber the liquid is discharged through a conduit R leading to the carburetor or other device to be supplied by fuel.

To permit discharge from the lower chamber during the filling of the upper chamber and the consequent closing of the valve L, an additional vent or atmospheric connection to said lower chamber is required. This may be formed by a tube S extending from the passage P downward through the partition B, but where such tube is open at all times, there is danger of a discharge of liquid therethrough from the lower tank. Such discharge may be occasioned by pressure of expansion in the upper chamber when there is no suction upon the system and the valves H' and O are both closed. Thus increased pressure in such chamber will force liquid downward into the lower chamber and upward through the tube S to the atmospheric connection P. The pressure in the upper chamber cannot exceed that required for unseating the valve O, but in practice it is found that to insure the proper seating of said valve O, it must be of sufficient weight to develop a pressure more than equal to the hydrostatic column in the tube S.

To overcome the difficulty just described, I have provided a valve for closing the tube S, which is automatically opened whenever there is suction in the upper chamber C, but will close when there is either atmospheric pressure or more than atmospheric pressure in said chamber. This construction comprises a fitting S' connected to a return-bent portion of the tube S and passing through

the partition B. In this fitting is a valve S² having upper and lower seats S³ and S⁴ with lateral inlet ports therebetween and arranged below the partition B. The valve S², which is preferably a ball, when resting on its lower seat, closes the tube S but opens communication between the upper chamber C and the lower chamber D. On the other hand, when there is suction in the upper chamber C, the valve S² will be lifted to its upper seat, cutting off communication between the upper and lower chambers and opening communication between the tube S and the lower chamber. This will permit the discharge of liquid from the lower chamber so that the tank can properly function when the valve L is closed.

The liquid, which is drawn into the upper chamber C through the conduit Q, may interfere with the operation of the float either by direct impact thereon or by causing agitation in the body of liquid in the chamber. To guard against such a result, I have provided a shield T which surrounds the float with sufficient clearance to provide for free movement thereof and which guards said float from impact of the incoming fluid. As shown, this shield T is of slightly conical or tapering form, being provided at its upper end with a flange T' clamped between the head or cover E and the body A of the tank. At one side the shield in its upper portion is radially inwardly depressed to form a groove or channel T² to which the conduit Q connects. A strainer Q' is also arranged in this channel, being flanged at its upper end and supported upon the flange T'. Thus the incoming liquid will discharge from the channel T² out of line with the float and will have no influence in disturbing said float.

In the complete operation the valves H and H' are alternatively seated and unseated by the combined action of pneumatic, hydrostatic and gravity pressures. Whenever there is suction in the connection F, this will assist in holding either the valve H or the valve H' to its seat and will therefore temporarily resist the opening of said valves by other forces, gravity or hydrostatic. Therefore, a fluttering of the valves, due to slight changes in pressure conditions, is avoided. The valve L being normally open and automatically opening by gravity will permit the free flow of fluid from the upper to the lower chambers. The velocity of discharge is variable, being greatest when there is the least fluid in the lower chamber and lessening as the lower chamber is filled with fluid. Such variable discharge is effected by the discharge nozzle L', which tends to hold the discharging liquid in an unbroken column. Therefore, the hydrostatic pressure of such column is added to the force discharging from the liquid and will consequently in-

crease the velocity when the column is longest.

When the valve H' is closed and the valve H opened, the suction operating upon the valve O will lift the same to an upper seat O^2 , this cutting off the suction connection to the atmospheric connecting passage P . The sealing of the valve O on the seat O^2 is not, however, complete so that whenever the valve H is closed, the pressures below and above the valve O will equalize, permitting the latter to fall by gravity. Thus, in operation, the chamber C will be alternately filled and discharged and at all times free feeding of the liquid from the lower chamber D is permitted.

What I claim as my invention is:

1. A vacuum tank comprising an upper compartment, suction means for filling the same, a lower compartment, a valve-controlled passage between said compartments, and means operated by suction in the upper compartment for opening an atmospheric vent to said lower compartment.

2. A vacuum tank comprising an upper compartment, suction means for filling the same, a lower compartment, a downwardly opening check valve controlling a passage between said compartments, an atmospheric vent for said lower compartment, a check valve for closing the same against internal pressure, and means operated by suction in the upper compartment for opening said check valve.

3. A vacuum tank comprising a casing having an upper and lower compartment, suction operated means for filling the upper compartment, a downwardly opening check valve controlling the passage between said upper and lower compartments, a vent tube for said lower compartment passing upward to said upper compartment, a check valve for closing said vent tube against pressure in said lower compartment, and a passage from said upper compartment to said check valve for opening the same by suction in said upper compartment.

4. A vacuum tank comprising upper and lower compartments, suction operated means

for filling said upper compartment, a check valve between said upper and lower compartments permitting downward discharge of liquid, an atmospheric vent passage for said lower compartment, a passage between said lower and upper compartments, and a common check valve controlling said passages operated by suction in the upper compartment to close the passage between said compartments and automatically closing said vent passage and opening the passage between compartments when relieved of such suction.

5. A vacuum tank comprising upper and lower compartments, suction operated means for filling the upper compartment, a check valve controlled passage permitting discharge from said upper to said lower compartments, a second passage between said upper and lower compartments, an atmospheric vent passage for said lower compartment, and a common check valve for alternatively closing the second passage, an atmospheric vent passage operated respectively by suction in the upper compartment and by gravity.

6. In a vacuum tank, the combination with a casing having a partition therein dividing the same into an upper and a lower compartment, a suction operated means for filling the upper compartment, a downwardly opening check valve controlling the passage from said upper to said lower compartment, an atmospheric vent tube extending through said upper compartment into said lower compartment and return-bent, a fitting in said return-bent portion of said tube extending through said partition and provided with a lateral port communicating with said lower compartment, and a check valve in said fitting seating by gravity to close connection between said lateral port and atmospheric vent tube and lifted by suction in the upper compartment to open said vent tube and to close communication between said upper and lower compartments.

In testimony whereof I affix my signature.

WILFRED O. CHASE.
